UNITED STATES PATENT OFFICE.

AQUILA R. BRAUN, OF SYRACUSE, NEW YORK, ASSIGNOR, BY MESNE ASSIGNMENTS,
TO LIBERTY NATIONAL BANK, TRUSTEE, OF SYRACUSE, NEW YORK.

PRESSING MACHINE.

Application filed February 20, 1924. Serial No. 693,960.

To all whom it may concern:

Be it known that I, AQUILA R. BRAUN, a citizen of the United States, and a resident of Syracuse, in the county of Onondaga 5 and State of New York, have invented a certain new and useful Pressing Machine, of which the following is a specification.

This invention relates to pressing machines, such as are used in pressing clothes, 10 garments, laundry and the like, and particularly clothes, and has for its object a particularly simple and efficient means for drying the garment or removing the moisture from the garment or other article being pressed 15 while the garment is being pressed and as soon as the moisture or steam is generated by the heat from one or both of the pressing elements, and while it is heated, without bringing colder air in contact therewith, 20 which colder air condenses the moisture, so that it is absorbed by the garment and hence harder to remove, which means is particularly simple and economical in construction, readily applied to the pressing machine and 25 highly efficient and rapid in operation. In other words, the invention consists in means for removing the moisture while in vapor form from the garment before it has been condensed by colder air, as when the moisture 30 is removed by blowing or by drawing air by suction through the garment. In both the blowing and withdrawing by suction or vacuum drying processes, the colder air condenses the vapor in the garment and 35 this condensed vapor or water is difficult to remove and requires a large volume of air over a comparatively long period of time, to evaporate and remove it. In blowing and vacuum processes, the moisture cannot be 40 efficiently removed during the pressing operation but the pressing is first performed and then the passing of the current of air either by blowing or by suction is performed, while, with my apparatus, the drying process 45 takes place almost completely during the pressing operation without bringing the outside colder air in contact with the garment or the vapor while in the garment.

The invention consists in the novel fea-

tures and in the combinations and constructions hereinafter set forth and claimed. 50

In describing this invention, reference is had to the accompanying drawings in which like characters designate corresponding parts in all the views. 55

Figure 1 is a side elevation of one form of machine embodying my invention, the press head being shown as closed.

Figure 2 is a fragmentary front elevation partly in section of the buck and press head 60 and contiguous parts.

Figure 3 is a diagrammatic view similar to Figure 1, showing the position of the drying means when the press head is partly open. 65

Figure 4 is a diagrammatic view similar to Fig. 2 showing the upper press head as partly open.

Figure 5 is a transverse sectional view through the upper press head. 70

Figures 6 and 7 are fragmentary face views of the press head and the buck, respectively.

Figure 8 is a fragmentary view showing the means for opening and retarding the 75 opening movement of the press head.

This invention comprises the combination with cooperating pressing elements of a pressing machine having relative movement one toward and from the other, one of said 80 elements usually the upper one having ventilating passages provided in and extending through the upper and lower faces thereof for permitting the natural escape of the water vapor as soon as it is generated in the 85 garment or other article being pressed and means for displacing the moisture laden air above the upper face of the upper element and replacing it with comparatively dry air having a greater affinity for moisture. 90 It, also, preferably includes means for heating the air above the upper face of the upper element, so that it has a greater affinity for moisture, and for retarding the heated air on the upper face of the head a sufficient 95 time, so that it can most efficiently absorb the moisture before being replaced by drier air.

The invention further consists in means for passing a current of air over the upper face of the lower element or the garment thereon immediately upon a partial opening 5 of the press head in order to blow off any vapor rising from the garment after the press is opened and means for momentarily retarding the full opening movement of the pressing head, in order that the lower face 10 of the press head may serve as a guide to direct such current of air across the upper face of the buck or the garment thereon.

I have here illustrated my invention as embodied in a foot press or manually operated 15 machine having a stationary lower buck and upper movable press head, although it may be embodied in a machine operated by power.

1, designates the lower buck which is mounted on a suitable bracket or goose neck 20 2, which, in turn, is mounted on a table 3 supported by a frame or legs 4. 5 designates the press head, which is carried by a yoke or frame lever 6 pivoted at 7 to an upright 8 rising from the rear leg of the 25 frame 4. The yoke or frame lever 6 is actuated in any suitable manner, here shown as by a toggle consisting of links 9 and 10 pivoted respectively at 11 to the rear arm of the yoke lever 6 and at 12 to the 30 lower end of the frame 4, these links being pivoted together at 13. The link 10 is shown as formed rigid with a forwardly extending pedal 14 having a foot plate 15 at its front end. The yoke is provided with a 35 suitable counterweight 16, which tends to open the press head, and also a spring 17 is usually connected to the treadle lever 14 and pulls upwardly thereon. By depressing the pedal 14, the toggle links 9 and 10 are moved from a folded to a straight position, thus bringing the press head 5 down on to the lower buck 1 into pressing position.

In the machine here shown, the head is 45 held in pressing position by a latch 18, which, when the treadle 14 is depressed, ratchets into engagement with a hook 19 on the base of the machine this latch being pivoted at 20 to the lever 14 and being weighted 50 at 21, the weight being so arranged that it tends to move the latch into engagement with the hook 19. To open the machine, the latch is tripped in any suitable manner here shown as by a pedal 22 pivoted at 23 to the 55 frame and having one arm thereof arranged to push upwardly on the weighted end 21 of the latch 18. When this lever 22 is depressed, obviously the latch will be moved out of engagement with the hook 19 and the 60 counterweight 16 and spring 17 will be free to act to open the press. The lever 22 is known in shop parlance as a kick off lever.

The construction of the operating means 65 for the press head forms no part of this invention and, in so far as this invention is

concerned, it is immaterial how the press head is operated. Also the buck 1 and press head 5 are formed hollow for receiving a heating medium as steam in the usual manner and one of these elements, as the lower buck 1, is formed with perforations 25 through which steam may be projected through the face of the buck into the garment, the passage of steam through these 70 perforations 25 being controlled by a valve 75 located within the housing 26, Fig. 1, and operated by an endwisely movable rod 27, which, in turn, is actuated by a pedal 28, 80 all of which will be understood by those skilled in the art.

The construction of the means for steaming the garment forms no part of this invention. It is material only in so far as means are provided for steaming the garment, although the garment may be moistened in any other manner.

In pressing garments, the buck and head are usually provided with padding to prevent a shiny surface being formed on the garment. These pads are a source of trouble, as they accumulate moisture which retards the drying of the garment. In this pressing machine, the pads are eliminated and, in order to prevent a shine being formed on the garment being pressed, the 90 faces of the buck 1 and press head 5 are covered by wire mesh screens designated 1^a and 5^a respectively, the margins of these screens being folded over the edge of the buck or the head and the screens being held 95 in position by tension springs 28^a hooked at their ends to the margins of the screens, the springs passing transversely under the buck or over the head, as seen in Figs. 1 and 2.

In order to permit the moisture to pass out of the garment being pressed, as soon as it is formed into a vapor by the heat of the pressing elements or as soon as it is projected on or through the garment, the upper press head 5 is provided with perforations, ventilating holes or outlet passages 29, Fig. 5, extending through its upper and lower faces and as nearly as possible preferably throughout the entire area 100 of the face of the press head.

In the illustrated embodiment of my invention, the upper press head is heated by a channel 30 extending around the press head through which steam is passed and the holes 29 are formed in the portion inclosed by this channel and also on the margin of the press head outside of the channel 30, as shown in Fig. 5, but there are no 110 passages directly beneath the channels 30 principally because it is an expensive operation providing or coring out passages extending through the channels. However, in some types of presses, known as edge presses, it is preferable to have passages 29 located 115 120 125 130

outside the channels and at the edges of the press head. Owing to these passages 29, the moisture which is placed in the cloth by the steaming operation and which is generated or vaporized in the moistened cloth by the heat of the buck 1 and the head 5 passes immediately out through the passages 29 as soon as it is formed, during the pressing operation and no cold outside air comes in contact therewith while this moisture is in the garment or where it can condense in the garment.

The means for removing the moisture laden air from the upper side of the press head 5 and from the upper ends of the openings 29 comprises means for passing a current of air across the upper side of the press head 5, this means being shown as a fan or blower 31 preferably movable up and down with the press head 5 and arranged to blow horizontally across the upper side of the buck 5.

The means for heating the air, so that it will have a greater affinity for moisture and hence pick up the moisture passing through the passages 29 more quickly, or the means for permitting the air to be heated and for retarding it long enough in its passage over the upper face of the head 5, so that it will have time to most efficiently absorb or pick up the vapor coming out of the passages 29, as here shown, comprises a housing 32 enclosing the upper side of the press head 5 and having an inlet for receiving air from the fan 31 and an outlet 33, this outlet being contracted or the housing be shaped so that the air is retarded or held back in its movement through the housing, and being held back is heated by the heat from the steam in the channels 30, and being heated has a greater affinity for moisture. The inlet and outlet are usually located at opposite ends of the head.

The blower 31 is here illustrated as a fan actuated by an electric motor 34 carried at the entrance end 35 of the housing, the entrance being provided with means for projecting air across the face of the upper buck 1 or the garment thereon when the head is part way open or during the opening movement of the head.

As here shown, the entrance is formed with an outlet 36, which is normally closed or partly closed or obstructed by the margin of the lower buck or the garment thereon when the press is closed, as the opening 36 is opposed and close to the end of the buck 35 when the press is closed. This outlet 36 also permits the escape of air in case the retarding effect becomes too great and would otherwise cause the air to back up on the fan or press downwardly in the openings 29. The air, in order to work most effectively, must be passed through the casing only fast enough to be heated and remove the moisture

by an absorption action and must not be passed through the passage so fast as to hold or cut off the moisture in the holes 29, and not too slow as to cause the air to back up into the holes 29. The outlet 36 acts both to prevent the air passing too fast and too slow through the housing. If the air passes too fast through the housing, the moisture will dam up in the passages 29, as it is only the pressure of the moisture that forces it out of the passages 29 and there is no atmospheric pressure back of the passages 29 to force it out when the press head is closed; or, in other words, it is not possible to create a suction through the passages 29 for the reason that there is no air pressure to force upwardly through the passage 29 and, if air passes too fast through the housing 32, a back pressure will be created in the holes 29.

As before mentioned, the press head is opened by operating the kick off pedal 22, which disengages the latch 19 from the hook 18 and permits the counterweight 16 and spring 17 to act. The means for delaying the opening movement of the press when the press head is slightly raised, in order that the press head may guide the current of air from the passage 36 across the face of the buck or across the garment thereon when the press head is slightly raised, as shown in Fig. 4, may be of any suitable form, size and construction, and, as here shown, comprises an escapement device operated by the kick off lever 22, this escapement device comprising a detent 37 carried by the kick off lever 22 and normally out of the path of the shoulder 38 on the pedal lever 14. When the kick off lever is operated, the detent 37 moves into the path of the shoulder 38 and hence retards the opening or upward movement of the treadle 14 as long as the operator holds his foot on the kick off pedal 22. But momentarily natural operation of the kick off pedal will delay the operation of the press head momentarily long enough to allow a puff of air to pass over the lower press head and carry away any moisture clinging to the garment. The engaging surfaces of the detent 37, and the shoulder 38 are so arranged that the shoulder 38 tends to cam the detent 37 out of engagement with the shoulder 38 when the foot is removed from the kick off pedal 22.

During the retarding of the opening movement of the press head, the heated air also blows out through the holes 29 on to the garment on the lower buck and also acts to remove the moisture rising from such garment, the force of the amount of air passing through the holes depending on the extent to which the housing 32 or the contracted outlet holds back the air and the extent to which the air is heated and expanded in the housing.

This invention is particularly advanta-

geous in that the moisture is removed as soon as it is present or generated by the heated pressing elements and no colder outside air comes in contact with this moisture and hence there is no condensation to be removed from the garment and hence the drying operation is particularly efficient and rapid and takes place and is practically completed as soon as the pressing operation is completed.

10 What I claim is:

1. In a pressing machine, a heated lower buck, a press head movable toward and from the lower buck and means for supporting and operating the press head; said press head being formed with ventilating passages opening through its upper and lower faces for permitting the escape of vapor during the pressing operation, means for removing the moisture laden air from above the upper ends of said passages and supplying comparatively dry air above the upper ends of said passages.

2. In a pressing machine, a heated lower buck, a press head movable toward and from the lower buck and means for supporting and operating the press head; said press head being formed with ventilating passages opening through its upper and lower faces for permitting the escape of vapor during the pressing operation, means for supplying and confining heated air above the upper face of the press head and at the upper ends of said passages.

3. In a pressing machine, a heated lower buck, a press head movable toward and from the lower buck and means for supporting and operating the press head; said press head being formed with ventilating passages opening through its upper and lower faces for permitting the escape of vapor during the pressing operation, means for confining heated air above the upper face of the press head and at the upper ends of said passages, and means for removing the moisture laden air and replacing it with relatively dry air.

4. In a pressing machine, a lower buck, a press head movable toward and from the lower buck and means for supporting and operating the press head; said press head being formed with ventilating passages opening through its upper and lower faces for permitting the escape of vapor during the pressing operation, a housing on the upper side of the press head and having an inlet at one end for air and an outlet at its other end and means for forcing air through the housing.

5. In a pressing machine, a heated lower buck, a heated press head movable toward and from the lower buck and means for supporting and operating the press head; said press head being formed with ventilat-

ing passages opening through its upper and lower faces for permitting the escape of vapor during the pressing operation, a housing on the upper side of the press head and having an inlet at one end for air and an outlet at its other end, the outlet being contracted whereby the outlet of the air is retarded and the air held back and heated in the housing by the heat from the press head whereby the air has a greater affinity for moisture and means for forcing air through the housing.

6. In a pressing machine, a lower buck, a heated press head movable toward and from the lower buck and means for supporting and operating the press head; said press head being formed with ventilating passages opening through its upper and lower faces for permitting the escape of vapor during the pressing operation, and means for passing air over the upper face of the press head across the upper ends of said passages.

7. In a pressing machine, a heated lower buck, a heated press head movable toward and from the lower buck and means for supporting and operating the press head; said press head being formed with ventilating passages opening through its upper and lower faces for permitting the escape of vapor during the pressing operation, a housing mounted on the upper side of the press head and having an air inlet and an outlet end, and means for passing air through the housing, said means being constructed to retard the passage of air whereby a body of air is held in the housing to facilitate the absorption of moisture passing through said passages.

8. In a pressing machine, a lower buck, a press head movable toward and from the lower buck and means for supporting and operating the press head; said press head being formed with ventilating passages opening through its upper and lower faces for permitting the escape of vapor during the pressing operation, a housing mounted on the upper side of the press head and having an inlet and an outlet, the outlet being contracted whereby the passage of air is retarded through the housing to hold the air back in the housing a sufficient time to absorb the moisture passing through the passages and a blower mounted on the press head at the air inlet of the housing.

9. In a pressing machine, a lower buck, a press head movable toward and from the lower buck and means for supporting and operating the press head; said press head being formed with ventilating passages opening through its upper and lower faces for permitting the escape of vapor during the pressing operation, and a blower mounted on a press head at one end thereof and

arranged to project a current of air across the upper side of said head above said passages.

10. In a pressing machine, a lower buck, a press head movable toward and from the lower buck and means for supporting and operating the press head; said press head being formed with ventilating passages opening through its upper and lower faces for permitting the escape of vapor during the pressing operation, and means for passing a current of air across the upper face of the head and across the face of the lower buck when the press head is open and means for delaying the opening of the press head after it has been partly opened whereby a current of air is guided across the lower buck by the face of the press head when in partly open position.
20. 11. In a pressing machine, a lower buck, a press head movable toward and from the lower buck and means for supporting and operating the press head; said press head being formed with ventilating passages opening through its upper and lower faces for permitting the escape of vapor during the pressing operation, and a blower mounted on a press head at one end thereof and arranged to pass a current of air across the upper side of said head around said passages, said blower being also provided with an outlet arranged below the face of the press head and directed to discharge across the buck, said outlet being obstructed by the lower buck when the press head is closed.
12. In a pressing machine, a lower buck, a press head movable toward and from the lower buck and means for supporting and operating the press head; said press head being formed with ventilating passages opening through its upper and lower faces for permitting the escape of vapor during the pressing operation, and a blower mounted on a press head at one end thereof and arranged to pass a current of air across the upper side of said head around said passages, said blower being also provided with an outlet arranged below the face of the press head directed to discharge across the buck, said outlet being obstructed by the lower buck when the press head is closed, and means for opening the press head and delaying the opening movement thereof when the press head is in partly open position whereby the press head guides the current of air across the upper face of the lower buck.
13. In a pressing machine, a heated lower buck, a heated press head movable toward and from the lower buck and means for supporting and operating the press head; said press head being formed with ventilating passages opening through its upper and lower faces for permitting the escape of vapor during the pressing operation, a hous-

ing mounted on the upper side of the press head and having an air inlet and an outlet, a blower mounted at the inlet of the housing, said blower being also formed with an outlet arranged below the face of the press head and directed to discharge across the face of the buck and to be obstructed by the edge of the buck when the press head is closed.

14. In a pressing machine, a lower buck, a press head movable toward and from the lower buck and means for supporting and operating the press head; said press head being formed with ventilating passages opening through its upper and lower faces, means for passing a current of air across the upper face of the head and means for delaying the opening of the press head after it has been partly opened whereby the air blows out through such passages toward the lower buck.

15. In a pressing machine, a lower buck, a heated press head movable toward and from the lower buck and means for supporting and operating the press head; said press head being formed with ventilating passages opening through its upper and lower faces, a housing on the upper side of the press head, means for passing a current of air into the housing and means for delaying the opening of the press head after it has been partly opened whereby the air passes through such perforations toward the face of the lower buck.

16. In a pressing machine, cooperating pressing elements, one movable toward and from the other, means for supporting and operating the movable element, the upper pressing element being heated and formed with ventilating passages opening through its upper and lower faces, a housing mounted on the upper side of the upper pressing element, means for passing a current of air into the housing, and means for delaying the opening of the press after it has been partly opened whereby the air passes through such passages toward the face of the lower pressing element.

17. In a pressing machine, cooperating pressing elements, one movable toward and from the other, means for supporting and operating the movable element, the upper pressing element being heated and formed with ventilating passages opening through its upper and lower faces, a housing mounted on the upper side of the upper pressing element, and having an air outlet and an inlet means for passing the air into the housing, the housing being shaped to retard the passage of air therethrough, whereby it is heated and expanded in the housing.

18. In a pressing machine, cooperating pressing elements, one movable toward and from the other, means for supporting and operating the movable element, the upper

pressing element being heated and formed with ventilating passages opening through its upper and lower faces, a housing mounted on the upper side of the upper pressing element, and having an air outlet and an inlet means for passing air into the housing, the housing being shaped to retard the passage of air therethrough, whereby it is

heated and expanded in the housing, and means for delaying the opening of the press 10 after it has been initially partly opened.

In testimony whereof, I have hereunto signed my name, at Syracuse, in the County of Onondaga, and State of New York, this 1st day of February, 1924.

AQUILA R. BRAUN.
